UNITED STATES PATENT OFFICE.

DANIEL P. ANTHONY, OF TECUMSEH, MICHIGAN.

WIRE-FENCE MACHINE.

SPECIFICATION forming part of Letters Patent No. 662,662, dated November 27, 1900.

Application filed August 14, 1899. Serial No. 727,177. (No model.)

To all whom it may concern:

Be it known that I, DANIEL P. ANTHONY, a citizen of the United States, and a resident of Tecumseh, in the county of Lenawee and State 5 of Michigan, have invented new and useful Improvements in Wire-Fence Machines, of which the following is a specification.

This invention relates to a machine for making wire fences which consist, essentially, 10 of a number of longitudinal or main wires, transverse stay-wires, which cross the main wires at intervals, and tie-wires, which connect the main and stay wires at the crossings of the same.

15 The objects of this invention are to improve means for feeding the wires, to provide simple and reliable means for fastening the wires together, to provide means for crimping the main wires, to improve the construction of 20 the reel upon which the fence is wound, to provide means for easily removing the roll of fence from the reel, and to improve the machine in other respects.

In the accompanying drawings, consisting 25 of seven sheets, Figure 1 is a top plan view of my improved wire-fence machine on a reduced scale. Fig. 2 is a fragmentary horizontal section of the same, on the same scale, in line 2 2, Fig. 16. Fig. 3 is a fragmentary 30 section, on the same scale, of the reel upon which the finished fence is wound, showing the same collapsed. Fig. 4 is a fragmentary horizontal section in line 4 4, Fig. 7. Fig. 5 is a vertical section, on an enlarged scale, in 35 line 5 5, Fig. 2, showing the position of the movable reel-bearing when the reel is in use. Fig. 6 is a similar view showing the position of this bearing preparatory to removing the reel therefrom. Fig. 7 is a side elevation of 40 my wire-fence machine on a larger scale than Fig. 1 and viewed from the right-hand side. Fig. 8 is a fragmentary vertical section, on an enlarged scale, in line 8 8, Fig. 14. Fig. 9 is a cross-section, on an enlarged scale, in line 45 9 9, Fig. 8. Fig. 10 is a perspective view of one of the wire-twisting disks. Fig. 11 is a side elevation, partly in section, of my wire-fence machine viewed from the left side. Fig. 12 is a fragmentary section taken length- 50 wise through the feed mechanism of the stay-

wires. Fig. 13 is a cross-section of the same in line 13 13, Fig. 12. Fig. 14 is a fragmentary transverse section of my wire-fence machine in line 14 14, Fig. 16. Fig. 15 is a sectional view of one of the stay-wire cutters 55 and its operating mechanism in line 15 15, Fig. 14. Fig. 16 is a longitudinal sectional elevation of my fence-machine. Fig. 17 is a longitudinal section, on an enlarged scale, of one of the stationary main-wire grippers. 60 Fig. 18 is a similar view of one pair of movable main-wire grippers. Fig. 19 is a cross-section of the same in line 19 19, Fig. 18. Fig. 20 is a perspective view of a fragment of the wire fence which is produced by my machine. 65 Fig. 21 is a fragmentary vertical cross-section, on an enlarged scale, in line 21 21, Fig. 1, showing the position of the tying and twisting devices preparatory to connecting the stay-wire to the main wires. Fig. 22 is a 70 similar view showing the position of the tying devices when the stay-wire is deflected. Fig. 23 is a similar view showing the position of the same parts after a tie is applied to the stay and main wires. Fig. 24 is a 75 fragmentary vertical section in line 24 24, Fig. 23. Fig. 25 is a fragmentary vertical section, on an enlarged scale, of one of the tying devices, the section being taken at an oblique angle to the course of the stay and main wires in 80 line 25 25, Figs. 28 and 29, and showing the tying devices retracted and the main wire, stay wire, and tie-wire in place preparatory to connecting the same. Fig. 26 is a similar view showing the position of the parts when 85 the main and stay wires are clamped and the tie is partly formed. Fig. 27 is a similar view showing the position of the parts when the tie is finished and connects the main and stay wires. Fig. 28 is a bottom or face view 90 of the upper clamping-jaw and adjacent parts. Fig. 29 is a top or face view of the lower clamping-jaw and adjacent parts. Fig. 30 is a horizontal section in line 30 30, Fig. 25. Fig. 31 is a similar section in line 31 31, 95 Fig. 27. Fig. 32 is a perspective view of one of the cutting-dies whereby a tie-blank is cut from the wire-stock and bent around the crossing main and stay wires. Fig. 33 is a perspective view of one of the curling or clench- 100

ing dies whereby the tie is curled or clenched around the stay-wire on opposite sides of the main wire.

Like letters of reference refer to like parts in the several figures.

The wire fence which is produced by my fence-machine consists, essentially, of a number of longitudinal or main wires A A', transverse or stay wires B, which cross the main wires at right angles, and ties or tie-wires C, which connect the stay or main wires at the crossings of the same. The stay-wires are twisted or coiled with their ends around the outermost main wires A', as shown at b, Figs. 1, 2, and 20, and are provided between their ends with downward bands or crimps b', in which the intermediate main wires lie when connected with the stay wire. Each of the ties when completed has the appearance of the figure 8, as represented in Fig. 20, and is formed from a staple. This staple straddles the main and stay wires obliquely at the crossing of the same and bears with its bight or bend against the outer side of the main wire, while its ends are clenched or curled in opposite directions around the stay-wire on opposite sides of the main wire, as represented in Fig. 20. This means of connecting the main and stay wires is fully described in Letters Patent of the United States granted to me February 28, 1899, No. 620,090.

The main frame of the machine consists, essentially, of two side pieces D D' and a cross-piece D², connecting the upper front part of the side pieces. The main wires A A' are supplied in any suitable way and pass forwardly underneath a transverse guide-roller d on the rear part of the frame, thence forwardly through the grippers of the feeding device, thence forwardly through the tying and twisting devices which are arranged on the cross-piece and whereby the cross-stays are connected with main wires, thence forwardly and downwardly around guide-rollers d', thence rearwardly underneath guide-rollers d², thence upwardly and rearwardly and around a reel E, upon which the finished fence is wound in a roll. The main-wire-feed mechanism operates at intervals for feeding the main wires forward one space after each stay is fastened thereto, and the reel at the same time is turned in the proper direction for taking up the finished part of the fence.

The mechanism for feeding the main wires is best shown in Figs. 1 and 16 to 19 and is constructed as follows: F represents a slide or carrier which is arranged transversely in front of the guide-roller d and which is mounted with its ends on longitudinal guide-bars E', so as to be capable of a longitudinally-reciprocating movement in the frame. The slide is provided on its upper side with a pair of grippers f f' for each of the main wires, the feeding-grippers f being constructed to grasp the wire during the forward movement of the slide, but release the same during the backward movement thereof, and the

safety-gripper f' being constructed to grasp the wire if during the forward movement of the slide the wire is pulled by the reel faster than the forward movement of the slide, but is inoperative during the backward movement of the slide. The grippers are arranged one behind the other on the slide, the feed-gripper being arranged on the rear part of the slide and the safety-gripper on the front part of the slide. The body f² of the feed-gripper has a horizontal opening f³ for the passage of the wire and a recess f⁴ arranged in the central part of the body and intersecting the upper part of the wire-passage. f⁵ is a gripping or clutch roller arranged transversely in said recess and bearing with its lower side against the top of wire in the body, while its upper side bears against the back or top f⁶ of the recess. The back or top f⁶ of the recess inclines from its front end toward the rear end, so as to give the recess a rearwardly-contracted form. As the slide moves forwardly the gripping-roller crowds into the narrow rear part of the recess and bears firmly against the wire, whereby the latter is compelled to move with the slide. During the backward movement of the slide the roller moves into the wide front part of the recess and releases the wire, thereby permitting the slide to move backward without the wire. For convenience and cheapness in manufacturing, the recess in the gripper-body is preferably extended from one side of the body to the other. In order to prevent the roller from escaping laterally from said recess, the roller is provided with a peripheral groove f⁷ at its middle, which receives the upper part of the wire, whereby the latter serves as a key to prevent lateral displacement of the roller. The roller is yieldingly held in its operative position, so as to grip the wire promptly at the beginning of the forward movement of the slide, by a spring f⁸, bearing with one end against the front side of the roller and with its other end against the adjacent part of the body.

The safety-gripper is constructed substantially the same as the feed-gripper, with the exception that the top f⁶ of its recess inclines forwardly and its spring f⁸ bears against the rear side of its roller, so that the safety-gripper operates reversely to the feed-gripper. During the forward movement of the slide the roller of the safety-gripper is moved by its spring into the narrow front part of its recess, and if the reel tends to pull the main wire forward faster than the forward movement of the slide the roller of the safety-gripper immediately grasps the same and prevents the wire from being pulled through the feed-gripper.

g represents releasing or shifting pins, whereby the rollers of the safety-grippers are moved into the wide rear part of the recesses in the safety-grippers, so as to prevent the same from gripping the wires during the backward movement of the slide. The releasing-

pin of each safety-gripper slides lengthwise in a horizontal opening g' in the front part of its body and bears with its rear end against the front side of the gripper-roller when in its operative position. The releasing-pins of the several safety-grippers are connected to a shifting or releasing bar g^2 , which is arranged transversely in front of the slide, as represented in Fig. 1. This bar is yieldingly held in its foremost position, so that its pins are held out of engagement with the rollers of the safety-grippers, by springs g^3 , surrounding guide-rods g^4 , which are secured to the slide and bearing with their ends against the bar and a shoulder on the slide. The forward movement of the releasing-bar is limited by stops or shoulders g^5 , arranged on the guide-rods and engaging against the front side of the bar. The backward movement of the releasing-bar with reference to the slide is effected by engaging the bar or a part thereof with any suitable stationary part of the machine. As shown in the drawings, this is effected by two tappets g^6 , arranged on the front side of the releasing-bar and adapted to engage with a cross-plate H , which is secured with its ends to the supporting longitudinal bars F' . The tappets engage with the plate H during the last portion of the forward movement of the slide, so that the slide is permitted to complete its forward movement while the releasing-bar is held stationary, thereby causing the releasing-pins to engage the rollers of the safety-grippers and shift the same into the wide rear part of the recesses of the grippers, whereby these grippers are prevented from gripping the main wires. After the releasing-bar has been thus stopped and the safety-grippers have been rendered inoperative the same are held in this position by two catches g^7 . These catches are pivoted near the ends of the slide, and each catch is provided at its front end with an inwardly-projecting beveled hook or shoulder g^8 and with a rearwardly-projection tail g^9 . Each catch is turned and yieldingly held with its hook in the path of the adjacent end of the releasing-bar by a spring g^{10} . As the releasing-bar is held by its tappets engaging with the plate H the catches during their continued forward movement with the slide F engage the ends of the releasing-bar with the beveled side of their hooks and are thereby deflected outwardly, and when the hooks have passed in front of the bar the springs g^{10} turn the catches so that the shoulders of the hooks engage with the front side of the releasing-bar and hold the latter in its rearwardly-shifted position with reference to the slide and safety-grippers. The safety-grippers are held in this inoperative position by the catches g^7 during the entire backward movement of the slide, and the feeding and safety grippers move along the main wires without disturbing the latter. During the last portion of the backward movement of the slide the tails of the catches engage with the inclined faces of

two stationary stops or tappets g^{11} , whereby the catches are turned so as to disengage their hooks from the releasing-bar. This permits the releasing-bar and the releasing-pins to be moved forward with reference to the safety-grippers by the springs g^3 and causes the rollers of these grippers to again assume their operative forward position preparatory to moving forward with the slide during the next working stroke of the latter.

The forward and backward movement of the slide carrying the feeding and safety grippers may be effected in various ways, the mechanism for this purpose shown in the drawings being constructed as follows: I represent two reciprocating carriages which slide lengthwise in the machine in two ways i , arranged on the inner sides of the side pieces. Each of these carriages is provided on its upper side with a horizontal screw-rod i' , which passes loosely through an opening formed in the adjacent end of the feed-slide F and which is provided in front and in rear of said slide with screw-nuts i^2 i^3 . During the forward movement of the carriages the same move idly until the rear screw-nuts i^3 of the screw-rods engage with the rear side of the feed-slide, after which the latter moves forwardly with the carriages until the end of the forward stroke of the carriages. During the backward movement of the carriages the same move idly until the front screw-nuts i^2 of the screw-rods engage with the front side of the feed-slide, after which the latter moves backward with the carriages to the end of the backward stroke of the same. By adjusting the front and rear nuts on the screw-rods the amount of dead or independent movement of the carriages with reference to the feed-slide can be varied so as to vary the extent of the feed of the main wires during each forward movement of the carriages. When the front and rear screw-nuts of the carriages are separated considerably, the dead movement of the same produces a comparatively short stroke of the feed-slide and the main wires are fed forward only a short distance, whereby the cross or stay wires are attached to the main wires at short intervals. If the front and rear screw-nuts i^2 i^3 of the carriages are brought closer together, the dead movement of the carriages is reduced and the feed-slide is caused to move with the carriages during a greater portion of the reciprocating movement of the latter, thereby producing a correspondingly longer feed of the main wires and causing the stay-wires to be arranged farther apart on the main wires.

J represents the main driving-shaft, which is journaled transversely in the lower part of the side pieces and provided at one end with a driving-pulley J' .

J^2 is a transverse counter-shaft, which is driven from the main shaft by a pinion j , arranged on the main shaft and meshing with a gear-wheel j' on the counter-shaft.

J^3 is a transverse cam-shaft, which is driven

at each end by a gear-pinion j^2 , arranged on the adjacent end of the counter-shaft and meshing with a gear-wheel j^3 , which turns on an arbor j^4 , and a gear-pinion j^5 , connected with the gear-wheel j^3 and meshing with a gear-wheel j^6 on the adjacent end of the cam-shaft, as shown in Figs. 1, 7, 11, and 14.

The carriages are driven from the cam-shaft so that they reciprocate in unison; but the driving mechanism of each carriage is separate from that of the other carriage, and consists of a rock-lever K , provided on its front arm k with a lug or roller which engages with a cam k' on the cam-shaft and provided on its rear arm k^2 with a gear-segment k^3 , which meshes with an intermediate gear-wheel k^4 , a gear-wheel k^5 meshing with a gear-rack k^6 on the under side of the adjacent carriage and a gear-pinion k^7 , connected with the gear-wheel k^5 , meshing with the gear-wheel k^4 , as shown in Fig. 16.

L represents a number of detent-grippers whereby the main wires are gripped and prevented from being pulled forward by the reel while the feed-slide is moving backward and has no control over the main wires. One of these detent-grippers is provided for each main wire, and the several detent-grippers are mounted on the supporting-plate H . Each of the detent-grippers is constructed substantially the same as the safety-grippers, and consists of a body h , having a longitudinal passage h' for a main wire, a recess h^2 , intersecting said passage and provided with a forwardly-inclined top h^3 and a roller h^4 , arranged in the recess and held yieldingly in the narrow front portion thereof by a spring h^5 , as represented in Fig. 17. Each detent-gripper is also provided with a longitudinally-movable releasing-pin h^6 , which engages with the front side of the roller for moving the same into an inoperative position in the wide rear part of the recess and which is connected at its front end to a transverse shifting or releasing bar h^7 . The latter is yieldingly held in a projected position by springs h^8 , which are mounted on rods h^9 , whereby the releasing-bar h^7 is guided on the plate H . The projecting movement of the releasing-bar is limited by stops h^{10} , arranged on the front ends of the guide-rods h^9 . During the forward movement of feed-slide F the releasing-bar of the detent-grippers is moved backward, so that the rollers thereof do not grip the wires, but permit the same to move forwardly, and the bar is held in this position by two catches h^{11} , which are held with their hooks in engagement with the releasing-bar h^7 by springs h^{12} . During the last part of the forward movement of the feed-slide F two tappets h^{13} h^{13} , mounted thereon, engage with the tail of the catches and release the same from the detent-releasing bar, whereby the latter is projected and permits the rollers of the detent-grippers to grip the main wires. The detent-releasing bar remains in this position during the entire backward movement of the feed-slide

F. At the end of its backward movement the slide engages with the depending hooks h^{14} of longitudinal rods h^{15} , which are connected with the detent-releasing bar, and draws the same rearwardly sufficiently to enable the catches h^{11} to hold the same in position for shifting the rollers of the detent-grippers into an inoperative position preparatory to effecting the next forward feed of the main wires. By this construction and operation of the grippers the main wires are held against forward movement by the detent-grippers during the backward movement of the feed and safety grippers and the safety grippers prevent an excess forward movement of the wires while the same are being fed forward by the feed-grippers. It will thus be seen that the feed of the main wires by this means is always under the control of the grippers, so that the wires can at no time be displaced by the forward pull of the reel and produce an irregularity in the spacing of the stay-wires with reference to the main wires, which otherwise would be liable to occur.

Owing to the constant increase in the diameter of the roll of finished fence upon the reel the latter is driven by a frictional driving mechanism, which is so constructed that the reel tends to rotate as much or slightly more than is necessary for taking up the slack in the finished fence when the reel is empty, and as the diameter of the roll increases while the speed of the driving mechanism remains constant the frictional coupling permits the reel to slip on the driving mechanism, thereby insuring a full take-up of the slack of the fence and avoiding any injury to the same or to the machine.

The frictional driving mechanism for the reel, which is shown in the drawings, is constructed as follows: e represents the horizontal shaft of the reel, which is arranged transversely in the rear part of the frame and journaled with its ends in bearings $e' e''$ on the side pieces of the main frame. One end of the reel-shaft is provided with the driven member e^3 of a pair of co-operating friction-wheels, which comprise the essential parts of a friction clutch or coupling. The driving member e^4 of the pair of friction-wheels is mounted loosely on the reel-shaft and is provided on its periphery with a gear-rim e^5 . The driving friction-wheel e^4 is driven from the counter-shaft J^2 by a gear-pinion e^6 , secured to the counter-shaft and meshing with a gear-wheel e^7 , which is journaled on an arbor E' , a gear-pinion e^8 , connected with said gear-wheel e^7 , and meshing with the gear-rim e^5 on the driving friction-wheel, as represented in Figs. 1, 4, and 7.

e^9 is a coupling or clutch lever whereby the driving friction-wheel is pressed inwardly against the driven friction-wheel for coupling the same and rotating the reel to wind up the slack in the fence. This lever is pivoted so as to turn horizontally by means of a

convex knuckle e^{10} , formed on the outer side of the lever and engaging with a concave socket e^{11} , arranged on the outer end of the arbor E' , as shown in Fig. 4. The rear arm 5 e^{12} of the lever is bifurcated and pivotally connected with a presser-collar E^2 , which is arranged loosely on the reel-shaft and bears against the outer side of the driving friction-wheel. The front arm e^{13} of the coupling-lever is bifurcated at its end and adapted to be engaged by a cam e^{14} on the right-hand end of the cam-shaft. This cam is so timed that it engages with the front arm of the 10 coupling-lever the instant the feed-slide F begins to move forward the main wires, thereby causing the lever to be turned in the proper direction to press the driving friction-wheel against the driven friction-wheel and so turn the reel for winding the fence thereon. The cam e^{14} holds the coupling-lever in this position until the feed-slide reaches the 15 end of its forward movement, and then the cam leaves the lever, so as to permit the driving friction-wheel to disengage itself from the driven friction-wheel. The frictional contact between the two wheels of the frictional coupling is so adjusted that the driving-wheel slips on the driven wheel after all the slack in the fence during the feed operation 20 has been taken up.

After each intermittent forward movement of the main wires a stay-wire B is fed across the under side of the main wires. This wire is fed from the left-hand side of the machine 25 through a transverse guide m in the adjacent side piece of the frame and then passes through the cutting and guiding devices and is presented to the tying and twisting devices, which are arranged on the front side of the 30 cross-piece of the frame.

The mechanism whereby the stay-wires are fed is constructed as follows: M, Figs. 1, 12, and 13, represents a transversely-reciprocating gripper which is constructed substantially the same as the main-wire-feeding grippers f and provided in its body with a horizontal opening for the passage of the stay-wire and a spring-pressed roller m' , which is arranged in a rearwardly-contracted recess 35 m^2 in the gripper-body and bearing against the stay-wire. During the forward movement of the feed-gripper M the stay-wire is fed forwardly and presented to the guiding, cutting, twisting, and tying devices, and during the 40 backward movement of the gripper M its roller is released from the stay-wire to permit the gripper to move backwardly without the wire for taking a new hold preparatory to feeding the stay-wire forward another length.

m^3 represents a reciprocating chain or feed-belt arranged transversely on the left-hand side of the machine and passing with its receiving and delivery portions around receiving and delivery sprocket-wheels $m^4 m^5$, as 45 represented in Figs. 12 and 14. The upper part of the feed-belt is parallel with and slightly below the guide m and passes through

a horizontal guide-trough m^6 , which is secured to the adjacent stationary part of the frame.

m^7 represents a horizontal guide or supporting plate which is secured to the upper part of the feed-belt and which is provided at its front and rear ends with upright lugs $m^8 m^9$. The feed-gripper M for the stay-wire rests on this supporting-plate and is adapted to engage with its ends against horizontal adjusting-screws $m^{10} m^{11}$, arranged in the lugs $m^8 m^9$. The adjusting-screws $m^{10} m^{11}$ permit of producing a loose connection between the gripper M and the feed-belt for the purpose of adjusting the amount of feed of this gripper while retaining an invariable motion of the belt. By separating the adjusting-screws $m^{10} m^{11}$ considerably the feed-belt during its forward stroke moves idly until the rear screw m^{11} engages with the gripper M, after which the latter moves forward with the belt to the end of its forward stroke. During the subsequent backward movement of the feed-belt the same moves idly, while the gripper M 90 stands still until the front adjusting-screw m^{10} engages with the gripper, after which the latter moves backwardly with the feed-belt to the end of its backward stroke.

The feed-belt and its gripper may be reciprocated in any suitable way, the mechanism shown in the drawings for this purpose consisting of a rock-shaft m^{12} , arranged lengthwise on the outer side of the left-hand side piece and carrying the delivery sprocket-wheel m^5 at its front end, and a short transverse-shaft m^{13} , which is connected at its outer end with the rear end of the rock-shaft m^{12} by intermeshing miter gear-wheels m^{14} and which is provided at its inner end with a gear-pinion m^{15} , meshing with the gear-wheel k^5 , as shown in Figs. 12 and 16. The relative movement of the feed mechanism of the main wires and that of the stay-wire is such that when the main wires are being fed forward the feed-gripper of the stay-wire is moved backwardly, and when the feed-grippers of the main wires are moving backwardly the stay-wire is fed forwardly by its feed-gripper.

M' , Figs. 1 and 12, represents a stationary detent-gripper whereby the stay-wire is prevented from moving backwardly with the feed-gripper M. This detent-gripper is secured to the delivery end of the guide-trough m^6 and is constructed substantially the same as the feed-gripper M, the only difference being that the latter is movable, while the detent-gripper is stationary. Before passing to the feed-gripper M the stay-wire is preferably passed through a straightening device M^2 , as 125 shown in Fig. 1, consisting of a set of rollers arranged in a well-known manner for this purpose.

After the stay-wire has been fed forward and the proper length has been presented to 130 the tying and twisting devices it is cut off or trimmed at its trailing end from the stock of stay-wire, and it is also cut off at its advancing end, so as to obtain an exact length of

the stay-wire preparatory to connecting the same with the main wires. These cutters are arranged adjacent to the outer side of the twisting devices and are similar in construction, so that the following description of one cutter applies to both.

N N' represent the stationary and movable cutters whereby the stay-wire is cut. The stationary cutter N is of tubular form, so that 10 the wire can pass through the same, and it is supported on a bracket n, which is arranged on the adjacent part of the front side of the cross-piece of the main frame. The movable cutter N' slides vertically in ways n' on the 15 bracket and is raised and lowered by a connecting-rod n², which is connected at its upper end with the movable cutter and at its lower end to a crank n³. The latter projects forwardly from a rock-shaft O, which is journaled transversely in the lower part of the 20 frame and which is operated by means of two like cams o' o', arranged near opposite ends of the cam-shaft J³ and engaging with two like rock-arms o² o², arranged near opposite 25 ends of the rock-shaft O, as represented in Figs. 14 and 16. The cams o' o' are so timed that while the stay-wire is being fed forward the movable cutters are retracted below the opening in the stationary cutters, and after 30 the stay-wire has been fed forward the proper length the movable cutters are raised, whereby the rear cutters cut the trailing end of the stay-wire from the stock-wire and the front cutter trims off the surplus form the advancing end of the stay-wire. If desired, the front cutter may be dispensed with, in which case 35 the feed of the stay-wire must be nicely adjusted so as to feed the stay-wire an exact distance each time in order that the stay-wire will not interfere with the proper working of the adjacent twisting devices; but it 40 is desirable to employ the front cutter, because it avoids the necessity of keeping the stay-wire-feed mechanism adjusted accurately. After the stay-wire has been severed 45 the same is tied to each of the intermediate main wires where it crosses the same.

The tying devices at the several crossings of the stay and main wires are the same in 50 construction, and the following description of one tying device applies to all of them.

P P', Figs. 16, 21 to 23 and 25 to 31, represent a pair of upper and lower clamping-jaws which grasp the stay-wire and the adjacent main wire which crosses the same. The upper jaw P is stationary and secured to a bracket p, projecting forwardly from the cross-piece of the main frame. The lower jaw P' is vertically movable toward and from 60 the upper jaw and is secured to the upper end of a hollow plunger p', which is guided in a bracket p², arranged on the adjacent part of the cross-piece of the main frame. The faces of the clamping-jaws are provided with semicircular grooves p³ p⁴, which are arranged at right angles to each other and which receive the crossing main and stay

wires. Upon closing the clamping-jaws upon the crossed main wire and stay-wire the latter, which is arranged below the main wire, is raised to the same or substantially the same plane as the main wire, whereby the downward crimp or bend b' is produced in the stay-wire, as represented in Fig. 23. The lower clamping-jaw is raised and lowered by a horizontal rock-arm p⁵, pivoted at its rear end to a cross-bar p⁶ of the main frame and provided at its front end with a socket p⁷, which receives a knuckle at the lower end of the plunger p'. The lower jaw is lowered into its open or inoperative position by its weight and that of the plunger and rock-arm connected therewith, and this jaw is raised into its closed or operative position by a rocking ram p⁸, secured to the rock-shaft O and engaging with the rock-arm p⁵, as shown in Figs. 14 and 16. While the crossed main and stay wires are grasped by the clamping-jaws, a wire-tie C is applied to the same for fastening them together.

q represents an elongated vertical recess arranged centrally in the upper clamping-jaw and extending from the lower side to the upper side thereof. This recess is arranged obliquely over the junction of the crossed main and stay wires and is provided on its front side with a stationary cutter q' and on its rear side with an abutment or stop-wall q². The wire-stock Q, from which the tie is made, is fed through a horizontal opening q³ in the cutter and across the recess q until it abuts against the opposite wall q². q⁴ is a bifurcated upper die which moves vertically in the recess q and which cuts the blank for the tie from the wire-stock Q and then assists in forming the tie around the crossed main and stay wires. This upper die is secured to the lower end of a rod Q', which slides vertically in the upper bracket p. While in its uppermost position the upper die is above the opening q³ in the cutter and while in this position the wire-stock Q is fed across the recess q, as represented in Fig. 25. The upper die now descends and its cutting edge q⁵ severs the tie-blank from the wire-stock, and then the lower ends of the prongs q⁶ q⁷ of the upper die engage with the blank and carry the same downwardly in the recess q. The blank while being carried downwardly by the upper die remains in a horizontal position until the blank bears obliquely against the top of the crossed main and stay wires, after which the prongs of the upper die during the continued downward movement thereof bend the ends of the blank downwardly on opposite sides of the crossed main and stay wires in the form of a staple, as represented in Fig. 26.

The cutting edges of the stationary cutter q' and of the upper die are beveled, as shown at q⁸ q⁹, Figs. 28, 30, 31, and 32, so as to cut the blank obliquely from the wire-stock, thereby producing pointed ends on the blank. The stop-wall q² is correspondingly beveled

to fit the beveled advancing end of the wire-stock and permit the same to be fed fully into the recess. The adjacent prong q^7 of the upper die is beveled to fit the bevel of the stop-wall, thereby permitting the upper die to be reversed and so as to utilize the prong q^7 as the cutter when the other prong q^6 becomes worn. The upper end q^{10} of the recess q^{11} between the prongs of the upper die is rounded to fit the bend of the blank, and the corners q^{12} at the junction of sides q^{13} of the recess and the lower ends of the prongs are rounded, so that the bending of the blank into staple form is gradual and easy. The lower ends of the prongs of the upper die and the top and sides of the recess between them are preferably grooved, as shown at q' , Figs. 28, 31, and 32, so as to hold the tie-blank in engagement therewith.

20 r represents a circular recess formed axially with the lower clamping-jaw, and $r' r^2$ are oblique slots extending laterally from the circular recess. As the ends of the blank are bent downwardly by the prongs of the upper die these ends move downwardly through the slots $r' r^2$ and inwardly into the central recess r in the lower clamping-jaw, and the prongs of the upper die enter the slots $r' r^2$ and fill the same, whereby the prongs, together with the lower clamping-jaw, form a complete circular recess in which the staple-shaped tie-blank is confined.

S is a lower vertical movable die whereby the legs of the staple-shaped tie-blank are clenched or curled around the stay-wire on opposite sides of the main wire and which is secured to a rod S' , which slides in the upper portion of the hollow plunger, as shown in Figs. 21 to 23 and 25 to 27. This lower die is cylindrical in form and arranged in the circular recess of the lower clamping-jaw, and the upper end of this die is provided with a central deep depression s , which is adapted to bear against the under side of the crimp b' , two shallow depressions $s' s'$, which are arranged on opposite sides of the central depression and which are adapted to bear against the under side of the main wire on opposite sides of the crimp b' , and two curved curling or clenching depressions $s^2 s^2$, which are arranged on opposite sides of the central depression and at right angles to the shallow depressions $s' s'$ and which are adapted to engage with the ends of the staple-shaped tie-blank and curl or clench the same around the stay-wire on opposite sides of the main wire. While the clamping-jaws are closing on the main and stay wires and the tie-blank is severed from the stock and bent downwardly over the crossing wires by the upper die the lower die is in its lowermost position, as shown in Fig. 26. The lower die is then raised, and one of its curling depressions engages at one end with one of the depending ends of the tie-blank and bends or curls the same upwardly in one direction around the adjacent part of the stay-wire on one side of the main

wire, and the other curling depression of the lower die engages at a point diametrically opposite to the other curling depression with the other depending end of the tie-blank and curls the same upwardly and around the stay-wire on the opposite side of the main wire and in a direction opposite to that in which the first-mentioned tie end is curled, as represented in Figs. 20, 23, 27, and 33. After the tie has been applied to the crossed main and stay wires the lower clamping-jaw and die are lowered and the upper die is raised into the position shown in Fig. 25 to permit the wires to be fed forward preparatory to tying the next stay-wire to the main wire.

The upper and lower dies may be operated by any suitable mechanism, that shown in the drawings for this purpose being constructed as follows: s^3 is a rock-shaft arranged above the cross-piece D^2 of the main frame and provided with a number of forwardly-projecting rock-arms s^4 , one of which is connected with the slide-rod Q' of each upper die by a connecting-rod s^5 . The rock-shaft is operated at opposite ends by a pair of like rock-arms s^6 , which are pivoted at their front ends to the inner sides of the side pieces D^2 and which are connected at their rear ends by connecting-rods $s^7 s^8$ with rock-arms $s^9 s^8$, projecting rearwardly from the rock-shaft s^3 , as represented in Figs. 1, 7, 11, 14, and 16. The rock-arms s^6 are raised and lowered by a pair of like rocking cams $s^9 s^8$, secured to the rock-shaft O , as represented in Figs. 14 and 16.

s^{10} represents a number of cranks which project forwardly from the rock-shaft O , and one of which is connected with each of the lower slide-rods S' for operating the lower die, as shown in Figs. 14 and 16. It will thus be seen that the upper and lower dies, the lower clamping-jaw, and the cutters are all operated from the rock-shaft O .

The wire-stock Q for the tie-wires is fed by horizontally-reciprocating grippers T , one of which is arranged obliquely in front of each upper clamping-jaw. This gripper is constructed substantially the same as the feed-grippers for feeding the main wires and is mounted on a horizontal guide-bar t . When the upper die q^4 is raised, the gripper T moves forwardly or toward the upper clamping-jaw and feeds the wire-stock forward one space, and as the upper die descends the gripper T moves backwardly for obtaining a new grip upon the wire. The gripper is moved back and forth at the proper time by an upright rock-lever t' , pivoted to the upper bracket p and connected loosely with its lower arm to the gripper T and provided in its upper arm with a cam-slot t^2 , which is engaged by a projection t^3 on the upper slide-rod Q' , whereby the gripper T is moved back and forth during the downward and upward movement of the upper die. The wire-stock Q is prevented from moving backward with the tie-feed gripper T by a detent-gripper T' , which is mounted on the front end of the guide-bar t and which

is constructed the same as the detent-gripper of the stay-wire-feed mechanism.

After the tie-wires have been applied to the stay and intermediate main wires the ends of the stay-wire are twisted or coiled around the outer main wires A' by two twisting devices, which are arranged adjacent to the ends of the stay-wire and each of which is constructed as follows: U represents a twisting-disk arranged in front of the cross-piece D² of the main frame adjacent to the inner side of one of the cutters and provided on its rear side with a front hollow shaft-section u, which telescopes rearwardly into a rear hollow shaft-section u'. The adjacent outer main wire A' passes forwardly through the center of the rear and front shaft-sections and the twisting-disk. The latter is provided on its front side with a tangential groove u², which is arranged horizontally in line with the opening in the adjacent stay-cutter and below the main wire in the disk when the disk is at rest, as represented in Figs. 8, 21, and 23. While in this position the stay-wire is fed forward and passes through the groove u² of the left-hand twisting-disk, thence between the several guiding and tying devices, and thence through the groove u² of the right-hand twisting-disk and the opening of the right-hand stay-cutter. After the ties have been applied to the intermediate main wires and the stay-wire and the latter has been cut off the twisting-disk is turned a number of times in the direction of the arrow in Fig. 23, whereby the disk winds the projecting end around the outer main wire A', as shown at b, Fig. 20, and then the disk stops with its tangential groove in the proper position to receive the next stay-wire. The end of the stay-wire is directed into the groove of the disk and confined therein at the beginning of the twisting operation by a guide-plate u³, secured to the cross-piece and bearing against the front side of the disk. The rear shaft-section is journaled in a bearing u⁴ on the cross-piece D², but is held against lengthwise movement therein by collars u⁵ u⁶, arranged at the front and rear ends of the rear shaft-section and bearing, respectively, against the front side of the cross-piece D² and the rear end of the bearing u⁴. The front shaft-section is connected by a spline u⁷ with the rear shaft-section, so as to be able to slide lengthwise in the rear section, but be compelled to turn therewith. The front shaft-section is yieldingly held in its foremost position by a spring u⁸, interposed between shoulders on the front and rear shaft-sections, as shown in Fig. 8. As the end of the stay-wire is wound upon the outer main wire the twisting-disk recedes in the same measure as the coils of the stay-wire advance on the main wire, this axial movement of the disk being permitted by the yielding connection of the same with the rear shaft-section.

u⁹ is a gear-wheel which is mounted loosely on the rear section of the twister-shaft be-

tween two shoulders on the bearing u⁴ and which meshes with a vertically-reciprocating gear-rack U'. 70

u¹⁰ is a pawl which is mounted in a recess extending inwardly from the bore of the gear-wheel and held by a spring u¹¹ yieldingly in engagement with a tooth or shoulder u¹² on the periphery of the rear shaft-section, as shown in Figs. 8 and 9. Upon raising the gear-rack it turns the gear-wheel u⁹ in the direction of the arrow, and its pawl engages with the shoulder of the rear shaft-section and turns the same, together with the twisting-disk, in the proper direction for twisting the end of the stay-wire around the outer main wire. As the gear-rack moves downward the same turns the gear-wheel backward, during which movement of the wheel its pawl moves backward idly without turning the shaft-sections and twisting-disk. When the gear-wheel reaches the end of its backward movement, its pawl stands slightly in rear of the shoulder of the rear shaft-section, so as to be 90 in a position to engage the same and turn the twisting-disk during the next upward movement of the gear-rack.

u¹³ is a spring detent-pawl which is secured to the cross-piece D² and is adapted to engage with a recess u¹⁴ in the periphery of the front collar u⁵ of the rear shaft-section at the end of each forward turning movement and so hold the twisting-disk against backward movement with the driving mechanism. 95

U² is a gear-rack which is connected with the rear side of the gear-rack U' and arranged at right angles thereto, these gear-racks being preferably formed in one piece and guided in loops U³ on the rear side of the cross-piece D². 100

u¹⁵ is a transverse rock-shaft which is provided with two gear-wheels u¹⁶ u¹⁶, one of which meshes with the rear gear-rack U² of each twisting device, as represented in Figs. 1 and 16. This shaft is operated from the rock-shaft O by a gear-segment u¹⁷, pivoted on the adjacent side piece of the frame and meshing with a gear-pinion u¹⁸ on the adjacent end of the rock-shaft u¹⁵ and a rock-arm u¹⁹, mounted on the rock-shaft O and connected by a rod u²⁰ with the gear-segment u¹⁷. After the ends of the stay-wire have been twisted around the outer main wires the main wires, with the stay attached thereto, are moved forward one space preparatory to attaching the next stay-wire to the main wires. The guide-plate u³ of each twisting device is provided with a notch or recess u²¹ adjacent to the axial opening and tangential groove of the twisting-disk, as shown in Figs. 8 and 14, 125 which permits the twist on the stay-wire to pass through the guide-plate when feeding the wires forward.

As the stay-wire is fed forward across the main wires it is guided so as to be properly presented to the several tying devices and to the trimming-cutter, and it is also held in position so as to supply the stock for producing the crimps b' in the stay-wire by the fol-

lowing mechanism: V V' represent upper and lower guide-jaws, a pair of which is arranged between every two tying devices and between each outer tying device and the adjacent twisting device, as represented in Figs. 1, 14, and 21 to 24. The opposing faces of each pair of guide-jaws are provided with longitudinal grooves v v', which together form a passage for the wire, and the front ends 10 of these grooves are flared, so as to facilitate the entrance of the wire into the same. The guide-passages of the several guide-jaws are all horizontally in line with each other and with the tangential grooves in the twisting disks and with the spaces between the upper and lower clamping-jaws of the tying devices when the latter are retracted. The upper jaw of each pair of guide-jaws is capable of vertical movement and is guided 20 by means of a guide-rod v², projecting upwardly therefrom into socket v³, formed in a bracket v⁴ on the cross-piece D² of the main frame. The upper guide-jaw is yieldingly held in a depressed position by a spring v⁵, 25 bearing with its ends against the upper end of the guide-rod and screw-plug v⁶, which closes the upper end of the socket v³, as shown in Figs. 21 to 24. The downward movement of the upper guide-jaw is limited 30 by a shoulder v⁷, which is arranged on the bracket v⁴, as shown in Fig. 24, and which is engaged by the upper guide-jaw when the latter is in its lowermost position. The lower guide-jaw V' is pivoted at its rear end to the 35 lower end of the bracket v⁴, so as to swing vertically, and this jaw is yieldingly held in an elevated position in engagement with the upper guide-jaw by a spring v⁸, bearing against the under side of the lower guide-jaw.

40 When the clamping-jaws of the tying devices are separated and the guide-jaws are in their lowest position, the stay-wire is fed forward by its feed mechanism and passes from the right-hand cutter through the slot 45 of the adjacent twisting-disk and thence successively through the several pairs of guide-jaws and between the several pairs of clamping-jaws, as represented in Fig. 21, and thence through the slot of the right-hand 50 twisting-disk to the right-hand cutter. During the first part of the upward movement of the several lower clamping-jaws the stay-wire is cut off by the cutters and is deflected upwardly by each lower jaw between the 55 guide-jaws on opposite sides thereof, as shown in Fig. 22. The rear end of the groove in each upper guide-jaw is curved upwardly, as shown at v⁹, Figs. 21 to 23, to permit of this deflection in the stay-wire. The springs 60 of the upper guide-jaws are sufficiently stiff to prevent the same from being raised while the stay-wires are thus deflected between the guide-jaws, thereby causing the stay-wire to draw lengthwise from both ends thereof to 65 furnish the necessary stock for the deflections in the stay-wire. During the last part of the upward or closing movement of each

lower clamping-jaw the stay-wire is pressed upwardly on opposite sides of each intermediate main wire, whereby the downward 70 crimp b' is formed on the stay-wire around the lower side of the intermediate main wire, as represented in Fig. 23. While forming the crimps in the stay-wire the latter is drawn taut throughout its entire length, and the 75 depressed portions of the stay-wire which extended from one clamping device to another are lifted, together with the upper guide-jaws resting thereon, as represented in Fig. 23, the springs of the latter permitting of this 80 movement. By thus holding the stay-wire in a depressed position between adjacent tying devices during the first part of the upward movement of the lower clamping sufficient upward deflection of the stay-wire is 85 produced at each tying mechanism to furnish the necessary stock from which to form the crimp at each crossing, thereby avoiding stretching of the stay-wire and the consequent weakening of the same. During the 90 upward movement of the upper guide-jaw the lower guide-jaw is moved up with the same by the spring v⁸.

After the tying devices retract from the stay and intermediate main wires and the twisting devices have twisted the ends of the stay-wire around the outer main wires the main wires are moved forwardly, together with the stay-wire, and in so doing the stay-wire deflects the lower guide-jaws downwardly and 100 escapes therefrom. The lower guide-jaw is again moved upwardly by its spring against the upper guide-jaw after the stay-wire escapes. After the guide-jaws are released from the stay-wire the jaws are depressed into their 105 lower position, the upper spring v⁵ being stronger than the lower spring v⁸ and overcoming the latter.

The completed portion of the fence is moved step by step from the stay-fastening devices 110 forwardly, downwardly, and rearwardly and is then presented to a crimping mechanism, which crimps each main wire between the stay-wires, so as to permit the fence to contract and expand freely. This crimping 115 mechanism is shown in Figs. 2, 14, and 16 and is constructed as follows: W is a horizontal supporting-plate secured transversely to the side pieces of the frame between the lower guide-rollers d² and provided with a slot w, 120 which extends transversely of the machine.

w' represents a number of stationary crimping-jaws, which are secured to the top of the supporting-plate on one side of the path of the main wires.

w² represents a number of movable crimping-jaws, which are arranged on the supporting-plate on the opposite side of the path of the main wires and having a transverse movement toward and upon the stationary crimping-jaws. The opposing faces of each pair of crimping-jaws are corrugated, so that one fits into the other, whereby each main wire upon being pressed between the crimping-jaws is

crimped, as shown in Fig. 2. The movable crimping-jaws are connected so as to move back and forth together by a rod w^3 , which is arranged in the slot w below the main wires.

5 The forward or closing movement of the movable crimping-jaws is produced by an upright rock-lever w^4 , which has its lower arm connected by a link w^5 with the rod w^3 , while its upper arm is engaged on one side by a cam w^6 on the cam-shaft J^3 . The opening or backward movement of the movable crimping-jaws is effected by a cam w^7 , Fig. 14, which engages with the opposite side of the upper arm of the rock-lever w^4 . The crimping-jaws are projected with their upper sides above a straight line extending from the lower side of one guide-roller d^2 to the lower side of the other guide-roller d^2 , and each crimping-jaw is provided with a beveled or rounded front end w^8 , as shown in Fig. 16. While the crimping-jaws are open the fence is advanced one space, during which movement the stay-wire immediately in front of the jaws rides up the rounded or inclined front ends of the jaws to the top thereof and then drops off the abrupt rear ends of the jaws, whereby those portions of the main wires in rear of this stay-wire are caused to lie between the movable and stationary crimping-jaws of each pair. The jaws are then closed, whereby those portions of the main wires lying between the same are crimped, and then the jaws are opened preparatory to advancing the fence another step and crimping the next section of the main wires.

35 After the main wires have been crimped the completed fence is wound or rolled on the reel.

For the purpose of permitting the roll of finished wire fence to be easily removed from the reel the latter is made collapsible, and one of its end supports is made removable, as follows: x represents a number of reel plates or bars which are arranged lengthwise of the reel-shaft e and which are pivotally connected at their middle and near their ends by radial links x' with collars x^2 on the reel-shaft. Upon turning these links so that they project at right angles from the reel-shaft the reel-plates are spread apart and the reel is expanded to its fullest extent, as represented in Fig. 2, in which position the wire fence is wound upon the same. Upon turning the links into an oblique position, as shown in Fig. 3, the reel-plates are moved toward the reel-shaft and the reel is contracted, in which position the roll of wire fence can be easily removed from the same. The links are turned for expanding or contracting the reel by a shifting collar x^3 , sliding lengthwise on the reel-shaft and connected with the outer ends of a pair of links by connecting-rods x^4 , a hand-lever x^5 , pivoted to the frame adjacent to the reel-shaft bearing e' , and a connecting-rod x^6 , connected at one end with said lever and at its opposite end with said shifting collar x^3 . The outward movement of the

links is arrested when the reel is expanded to its fullest extent by the heels x^7 of the links, which bear against the adjacent part 70 of the pivot-supports when the reel is in this position.

x^8 represents a number of fastening pins or hooks whereby the advancing ends of the main wires are fastened to the reel for the 75 purpose of causing the fence to wind upon the reel. These pins are arranged in a row lengthwise of the reel and are secured with their inner ends to a longitudinal bar x^9 , which is arranged along the inner side of one 80 of the reel-plates, while their outer ends project through openings in the adjacent reel-plate, as shown in Figs. 2, 3, and 16.

The pin-supporting bar x^9 is pivoted to cranks x^{10} , which are formed on the outer 85 ends of the adjacent links x' . When the reel is expanded by the straightening of its links, the cranks shift the supporting-bar x^9 so that its pins project outwardly through the adjacent reel-plate, as represented in Figs. 2 and 90 16. In this position of the reel the advancing ends of the main wires are attached to the fastening-pins, which is done by forming loops x^{11} on the ends of the wires and slipping them over the pins, as shown in Fig. 16. 95 Upon turning the reel in the direction of the arrow when the main wires are thus fastened on the reel the fence is wound upon the reel. When the desired length of fence has been wound on the reel, the latter is collapsed by 100 moving its links and plates inwardly, and during this inward movement of the links the cranks x^{10} move the supporting-bar inwardly faster than the adjacent reel-plate, whereby the fastening-pins are drawn inwardly beyond the outer surface of this reel-plate, as represented in Fig. 3, thereby 105 releasing the loops of the main wires from the pins and permitting the removal of the roll of fence from the reel.

For the purpose of permitting the roll of fence to be removed from the reel without taking the reel out of the machine and disconnecting the same from its driving mechanism the right-hand bearing e' of the reel-shaft, which is adjacent to the driving mechanism, is stationary, while the left-hand bearing e^2 of the reel-shaft is made movable, as follows: Y represents a movable frame-section or supporting-foot which is pivoted at 115 its front end to the rear end of the left-hand side piece of the main frame by a vertical pivot y . The movable frame-section is provided on its upper side with a transverse bearing y' , in which a short shaft y^2 is journaled. 120 This shaft carries at its inner end the left-hand bearing e^2 of the reel-shaft. The bearing e^2 is cut out or recessed on one side, as shown at y^3 , Figs. 1, 5, and 6. When the reel is in use, the bearing e^2 is turned so that the 125 notch y^3 faces upwardly, as shown in Fig. 5, whereby the reel-shaft is prevented from being displaced by the lateral or forward pull which is exerted on the reel-shaft while wind-

ing the fence upon same. When it is desired to remove the roll of fence from the reel, the bearing e^2 is turned so that its recess y^3 faces upwardly, as shown in Fig. 6. In this position of the bearing e^2 the same can be freely moved outwardly, together with the movable frame-section, into the position shown by dotted lines in Fig. 2, which permits the roll of fence to be withdrawn lengthwise from the reel. The turning of the movable bearing e^2 is effected by a hand-lever y^4 , which is connected to the outer end of the short shaft y^2 , carrying the bearing e^2 .

Assuming that the fastening devices have just completed the operation of fastening a stay-wire across the main wires, the operation, briefly stated, of my fence-machine is as follows: The main-wire-feed grippers move forward and carry the main wires forward one space, during which time the stay-wire-feed gripper moves backward. The main-wire-feed grippers now move backwardly and the stay-wire-feed gripper moves forward and carries a length of stay-wire across the main wires. The cutters now cut off the stay-wire, and immediately thereafter the clamping-jaws close upon the intermediate main and stay wires and the tie-wires are applied to the same. As the tying devices recede from the main and stay wires the twisting devices twist the ends of the stay-wire around the outer main wires. While a stay-wire is being fastened to the main wires the crimping devices are operating upon a preceding section of the main wires and crimping the same. During the forward movement of the main wires the reel is coupled with the driving mechanism and the fence is wound upon the reel in the same measure as the main wires are fed forward by the main-wire-feed grippers.

I claim as my invention—

1. A wire-gripper comprising a body having a longitudinal opening for the passage of the wire, a recess which intersects said opening and which has an inclined back, and a roller arranged transversely in the recess and adapted to bear with one side against the inclined back thereof and with its opposite side against the wire in said opening, substantially as set forth.

2. A wire-gripper comprising a body having a longitudinal opening for the passage of the wire, a recess which intersects said opening and which has an inclined back, a roller arranged transversely in said recess and adapted to bear with one side against the back thereof and with its opposite side against the wire in said opening, and a spring which holds the roller yieldingly in the narrow part of said recess, substantially as set forth.

3. A wire-gripper comprising a body having a longitudinal opening for the passage of the wire, a recess which intersects said opening and which has an inclined back, a roller arranged transversely in said recess and adapted to bear with one side against the back thereof and with the opposite side against the

wire in said opening, and a shifting device whereby the roller is shifted into the wide part of said recess, substantially as set forth. 70

4. A wire-gripper comprising a body having a longitudinal opening for the passage of the wire, a recess which intersects said opening and which has an inclined back, a roller arranged transversely in said recess and 75 adapted to bear with one side against the back thereof and with its opposite side against the wire in said opening, a spring whereby the roller is yieldingly held in the narrow part of said recess, and a movable shifting-pin which 80 is guided in the body and whereby the roller may be shifted into the wide part of said recess, substantially as set forth.

5. In a wire-fence machine, the combination with the fastening devices whereby the transverse stay-wires are fastened to the longitudinal main wires, and the reel upon which the fence is wound, of longitudinally-movable feed-grippers which grasp the main wires during their forward movement and 90 feed the same forward and which release the main wires during their backward movement, and safety-grippers which move with the feed-grippers and which are constructed to grasp the main wires if the reel tends to pull the 95 same forward through the feed-grippers during the forward movement of the latter and to release the main wires while moving backwardly with the feed-grippers, substantially as set forth. 100

6. In a wire-fence machine, the combination with the fastening devices whereby the transverse stay-wires are secured to the longitudinal main wires, and the reel upon which the fence is wound, of longitudinally-movable feed-grippers which grasp the main wires during their forward movement and feed the same forward and which release the main wires during their backward movement, and detent-grippers which are constructed to 110 release the main wires while the same are being moved forward by the feed-grippers and to grasp the main wires so as to prevent the reel from pulling the same forwardly during the backward movement of the feed-grippers, 115 substantially as set forth.

7. In a wire-fence machine, the combination with the fastening devices whereby the transverse stay-wires are fastened to the longitudinal main wires, and the reel upon which 120 the fence is wound, of longitudinally-movable feed-grippers which grasp the main wires during their forward movement and feed the same forward and which release the main wires during their backward movement, 125 safety-grippers which move with the feed-grippers and which are constructed to grasp the main wires if the reel tends to pull the same forward faster than the forward movement of the feed-grippers and to release the 130 same while moving backwardly with the feed-grippers, and detent-grippers which are constructed to release the main wires during the forward movement of the feed-grippers and

to grasp the main wires so as to prevent the reel from pulling the same forwardly during the backward movement of the feed-grippers, substantially as set forth.

- 5 8. In a wire-fence machine, the combination with the fastening devices whereby the transverse stay-wires are fastened to the longitudinal main wires, and the reel upon which the fence is wound, of a longitudinally-mov-
10 able carrier, feed-grippers mounted on said carrier and provided with rollers adapted to grasp the main wires during their forward movement and to release the same during their backward movement, safety-grippers ar-
15 ranged on said carrier and provided with gripping-rollers adapted to grasp or release the main wires, a movable shifting-bar provided with shifting-pins, a stop with which said bar engages at the end of the forward movement of
20 the carrier and is shifted so that its pins move the rollers of the safety-grippers into an in-
operative position, a catch whereby the shifting-bar is held in its releasing position, a tappet adapted to engage with said catch at the
25 end of the backward movement of said car-
rier and release the shifting-bar, a spring whereby the shifting-bar is moved forward when released to permit the rollers of the safety-grippers to grasp the main wires, de-
30 tent-grippers arranged on a stationary sup-
port and provided with gripper-rollers adapt-
ed to grasp or release the main wires, a shift-
ing-bar provided with shifting-pins adapted to release the detent-gripper rollers from the
35 main wires, a shifting-rod connected at one end with the detent-gripper-shifting bar and adapted to be engaged by said carrier at the end of the backward movement of the latter for shifting the same into an operative position,
40 a catch which holds the detent-releas-
ing bar in its operative position, a tappet adapted to engage the last-mentioned catch and disengage the same from the detent-shift-
ing bar at the end of the forward movement
45 of the carrier, and a spring whereby the de-
tent-shifting bar is shifted into its inoper-
ative position when released by said catch, sub-
stantially as set forth.
9. In a wire-fence machine, the combina-
50 tion with the fastening devices whereby the transverse stay-wires are connected with the longitudinal main wires, of a movable slide provided with grippers whereby the main wires are fed forwardly, two longitudinally-
55 reciprocating carriages each of which is pro-
vided with adjustable stops adapted to en-
gage against the front and rear sides of said slide, substantially as set forth.
10. In a wire-fence machine, the combina-
60 tion with the fastening devices whereby the transverse stay-wires are connected with the longitudinal main wires, of a movable slide provided with grippers whereby the main wires are fed forwardly, two longitudinally-
65 reciprocating carriages each of which is pro-
vided with a horizontal screw-rod passing through said slide, and screw-nuts arranged

on each rod in front and in rear of the slide, substantially as set forth.

11. In a wire-fence machine, the combina- 70 tion with the fastening devices whereby the transverse stay-wires are fastened to the lon-
gitudinal main wires, and the reel upon which the fence is wound, of a feed mechanism whereby the main wires are fed forward in-
75 termittently, and a friction-coupling where-
by the reel is connected with the driving mechanism during the forward movement of the feed mechanism and disconnected there-
from during the backward movement thereof, 80 substantially as set forth.

12. In a wire-fence machine, the combina-
tion with the fastening devices whereby the transverse stay-wires are fastened to the lon-
gitudinal main wires, and the reel upon which 85 the fence is wound, of a feed mechanism whereby the main wires are fed forward in-
termittently, a pair of co-operating friction-
wheels one of which is connected with the reel and the other with the driving mechan-
ism, a rock-lever connected with one arm to 90 one of the friction-wheels, and a cam which is connected with the driving mechanism and which rocks said lever for engaging said fric-
tion-wheels when the feed mechanism moves 95 forwardly and releases said lever for disen-
gaging the friction-wheels when the feed mechanism moves backwardly, substantially as set forth.

13. In a wire-fence machine, the combina- 100 tion with the fastening devices whereby the transverse stay-wires are fastened to the lon-
gitudinal main wires, of a feed mechanism whereby the main wires are fed intermit-
tently past the fastening mechanism, and a 105 feed mechanism whereby the stay-wires are fed across the main wires at the fastening de-
vices, substantially as set forth.

14. In a wire-fence machine, the combina- 110 tion with the fastening devices whereby the transverse stay-wires are fastened to the lon-
gitudinal main wires, of a feed mechanism whereby the main wires are fed past the fas-
tening devices, a transversely-movable belt provided with a support and with adjusting-
115 screws on the front and rear ends of the sup-
port, and a gripper arranged on said support between said screws, substantially as set forth.

15. In a wire-fence machine, the combina- 120 tion with the fastening devices whereby the transverse stay-wires are fastened to the lon-
gitudinal main wires, of a feed mechanism which feeds the main wires past the fasten-
ing devices, a feed mechanism which feeds the 125 stay-wires across the main wires, and a cut-
ter mechanism which cuts off the lengths of stay-wires from the stock of wire, substan-
tially as set forth.

16. The combination with a pair of clamp- 130 ing-jaws which are adapted to hold two cross-
ing fence-wires, of a die arranged in one of
said jaws and adapted to hold a staple-shaped tie-wire over the crossing of said fence-wires,

and a die arranged in the other jaw and provided with two curling-faces which are adapted to engage with the ends of the tie-wire and curl the same around one of said wires on opposite sides of the other wire, substantially as set forth.

17. The combination with an upper and a lower clamping-jaw which are adapted to hold two crossing fence-wires, of an upper die arranged in a recess in the upper jaw and provided with a recess which receives a staple-shaped tie-wire and holds the same over the crossing fence-wires, and a lower die adapted to enter the recess of the upper die and provided with two curling-faces which are adapted to curl the ends of the tie-wire around one of said fence-wires on opposite sides of the other fence-wire, substantially as set forth.

18. The combination with the upper and lower clamping-jaws which are adapted to hold two crossing fence-wires, and each of which is provided with a recess, of a cutter arranged in the side of the upper jaw and provided with an opening for the passage of the tie-wire into the recess of the upper jaw and provided with a cutting edge adjacent to the opening of said cutter, whereby upon depressing the upper die a tie-blank is cut from the stock of wire and the blank is bent downwardly over the crossing fence-wires and the depending ends of the blank are inclosed by the bifurcation of the upper die and the recess of the lower die, and a lower die which is adapted to move upwardly into the bifurcation of the upper die and the recess of the lower die and which is provided with two curling-faces adapted to engage with the ends of the tie-wire and curl the same around one of the fence-wires on opposite sides of the other fence-wire, substantially as set forth.

19. The combination with the mechanism for feeding two fence-wires one across the other, of a twisting-disk provided with an axial opening through which one of said wires passes, and provided with a tangential groove which receives the other fence-wire, whereby upon rotating said disk the wire in its groove is twisted around the wire in its axial opening, substantially as set forth.

20. The combination with the mechanism for feeding two fence-wires one across the other, of a twisting-disk provided with an axial opening through which one of said fence-wires passes, and provided with a tangential groove in its face, which receives the other fence-wire, a hollow telescopic shaft through which the first-mentioned wire passes and which has a front section carrying the twisting-disk and a rear section journaled in a stationary bearing, a spline connecting said shaft-sections, a guide-plate arranged in front of the twisting-disk and provided with a notch for the passage of said wires, and a spring whereby the twisting-disk is yieldingly held against the guide-plate, substantially as set forth.

21. The combination with the mechanism

for feeding two fence-wires one across the other, of a twisting-disk mounted on a hollow shaft through which one of the fence-wires passes and provided with a tangential groove which receives the other fence-wire, a gear-wheel provided with a pawl which engages with a shoulder on said shaft and turns the latter forwardly but which permits the gear-wheel to turn backwardly without the shaft, and a reciprocating gear-rack meshing with the gear-wheel, substantially as set forth.

22. The combination with the mechanism for feeding two fence-wires one across the other, of a twisting-disk provided with an axial opening through which one of said fence-wires passes and provided with a tangential groove in its face which receives the other fence-wire, a hollow telescopic shaft through which the first-mentioned wire passes and which has a front section carrying the twisting-disk and a rear section journaled in a stationary bearing, a spline connecting said shaft-sections, a guide-plate arranged in front of the twisting-disk and provided with a notch for the passage of said wires, a spring whereby the twisting-disk is yieldingly held in engagement with the guide-plate, a gear-wheel provided with a pawl which engages with a shoulder on said shaft upon moving the wheel forwardly, a gear-rack meshing with the gear-wheel, and a detent-pawl engaging with a notch in a collar on said shaft, substantially as set forth.

23. The combination with the mechanism for feeding a transverse stay-wire and a longitudinal main wire one across the other, of a tying device provided with upper and lower clamping-jaws adapted to grasp the crossing wires, transverse wire-guides arranged on opposite sides of the clamping-jaws and each guide provided with an upper guide-jaw which is normally arranged with its face below the face of the upper clamping-jaw, and a spring whereby the upper guide-jaw is yieldingly held in a depressed position, whereby upon feeding a wire through the guides and across the tying device and then closing the clamping-jaws the wire is first deflected upwardly between the wire-guides by the rise of the lower jaw and then the depressed parts of the wire on opposite sides of the tying device are drawn upwardly and raise the upper guide-jaws, thereby furnishing the stock from which to form a crimp in the transverse fence-wire and permit the same to pass around the main wire, substantially as set forth.

24. The combination with the mechanism whereby a transverse stay-wire and a longitudinal main wire are fed one across the other, of a tying device provided with upper and lower clamping-jaws adapted to grasp the crossing wires, transverse wire-guides arranged on opposite sides of the clamping-jaws and each guide provided with an upper guide-jaw, an upright rod arranged on each guide-jaw and sliding in a support, a spring whereby the guide-jaw is yieldingly held in a depressed

position, and a stop which limits the downward movement of the guide-jaw, substantially as set forth.

25. The combination with the mechanism whereby a transverse stay-wire and a longitudinal main wire are fed one across the other, of a tying device provided with upper and lower clamping-jaws adapted to grasp the crossing wires, transverse wire-guides arranged on opposite sides of the clamping-jaws and each guide provided with upper and lower guide-jaws, an upright rod arranged on each upper guide-jaw and sliding in a support, a spring whereby each upper guide-jaw is held in a depressed position, a pivot connecting the rear end of each lower guide-jaw with the adjacent support, and a spring whereby each lower guide-jaw is yieldingly held against the underside of the companion upper guide-jaw, substantially as set forth.

26. In a wire-fence machine, the combination with a transverse row of crimpers each of which consists of a pair of corrugated jaws between which one of the fence-wires is fed, and shifting mechanism whereby one jaw of each pair is moved toward its companion jaw and the wire between the same is crimped, substantially as set forth.

27. In a wire-fence machine, the combination with a transverse row of crimpers each of which consists of a stationary corrugated jaw and a movable corrugated jaw, and a reciprocating rod connecting the movable jaws, substantially as set forth.

28. In a wire-fence machine, the combination with the fastening devices whereby the transverse stay-wires are connected with the longitudinal main wires, the reel upon which the fence is wound, and the guide-rollers whereby the fence is supported between the fastening mechanism and the reel, of a transverse row of crimpers arranged between two of said rollers and each crimpler consisting of a stationary corrugated jaw and a movable corrugated jaw, said jaws having rounded or beveled front ends and projecting with their

upper sides above a straight line drawn from the bottom of one roller on one side of the crimpers to the bottom of the roller on the other side of the crimpers, substantially as set forth.

29. The combination with the reel-shaft, of a number of reel-bars arranged lengthwise of the shaft, links connecting the bars with the shaft, a sliding collar arranged on the shaft, rods connecting the outer ends of some of the links with said collar, and a lever connected with said collar, substantially as set forth.

30. The combination with the reel-shaft, of a number of reel-bars arranged lengthwise of said shaft, radial links connecting the bars with the shaft, a supporting-bar arranged lengthwise along the inner side of one of the reel-bars, cranks arranged on the outer ends of the adjacent links and connected with said supporting-bar, and wire-attaching pins arranged on said bar and adapted to project beyond the adjacent reel-bar for receiving the ends of the fence-wires, substantially as set forth.

31. The combination with the reel-shaft, of a stationary bearing in which one end of the shaft is journaled, and a movable bearing in which the other end of the shaft is journaled, substantially as set forth.

32. The combination with the reel-shaft, of a stationary bearing on one side of the frame in which one end of the reel-shaft is journaled, a movable bearing arranged on a foot pivoted to the opposite side of the frame, a short shaft journaled in the movable bearing, a bearing for the opposite end of the reel-shaft arranged on the inner end of the short shaft and having a laterally-extending recess, and a handle arranged on the outer end of the short shaft, substantially as set forth.

Witness my hand this 5th day of August, 1899.

DANIEL P. ANTHONY.
